UNITED STATES PATENT OFFICE.

WILLIAM H. BREMMERMAN, OF FULTON, NEW YORK, ASSIGNOR TO OSWEGO FALLS CORPORATION, OF FULTON, NEW YORK, A CORPORATION OF NEW YORK.

TAPERED FIBROUS-MATERIAL BOTTLE AND THE LIKE.

Application filed March 14, 1924. Serial No. 699,274.

This invention relates more particularly to the formation of bottom closures for the tapered bodies or barrels of paper or other fibrous material bottles; and the objects and nature of the invention will be readily understood by those skilled in the art in the light of the following explanations of the accompanying drawings that illustrate what I now believe to be the preferred mechanical expression or embodiment of my invention from among other forms, constructions and formations within the spirit and scope thereof.

An object of the invention is the production of a tapered or conical so-called paper bottle with an improved permanent comparatively rigid bottom closure.

With this and other objects in view, my invention consists in certain novel features of construction and in combinations and arrangements as more fully and particularly explained and specified hereinafter.

Referring to the accompanying drawings forming a part hereof:

Fig. 1 shows in side elevation a so-called paper bottle embodying my invention.

Fig. 2 shows a portion of the paper bottle of Fig. 1, in sectional elevation.

Fig. 3 is a detail vertical section on an enlarged scale in an exaggerated manner showing a waterproofing and stiffening coating.

Fig. 4, shows certain mechanism in vertical section, and a paper disk and a paper bottle body in cross section and in sectional elevation respectively, all to illustrate a certain step in the method of forming paper bottles with permanent bottom closures, in accordance with my invention.

Figs. 5 and 6, are vertical sectional views illustrating additional steps in the method of bottoming paper bottles in accordance with my invention.

The paper bottle illustrated, embodies a barrel or body 1 in the form of a truncated cone, tapering upwardly from a bottom or base of relatively large diameter to a mouth or top of small diameter. In the particular example illustrated, this upwardly contracting tapered body is composed of a single flexible sheet of paper or so-called pulp or paper board material, of suitable shape, that is bent or rolled around a mandrel so that the longitudinal edges of the blank overlap. These overlapping edges are suitably secured together to form a preferably liquid tight per-

manent joint or seam 1^a, throughout the length of the tapered or conical paper material body. This tapered body, prior to the formation of the mouth portion and the bottom closure of the complete bottle, is of greater length than the tapered body of the completed bottle. This extra length of the tapered body is taken up in the formation of the bottle mouth and the bottom closure. The bottle mouth in the example illustrated, is formed by a metal neck or mouth ring 2, usually embracing and suitably attached to the upper edge portion of the paper body surrounding the small upper open end of the body. This neck ring forms the top rim of the bottle and usually provides the bottle mouth with a exterior annular bulge and with a depressed internal annular flange or seat for a removable paper disk, such as a milk cap, for sealing the bottle mouth. However, I do not wish to limit my invention to any particular mouth or neck formation nor to any particular manner of forming or construction of the tapered paper material body, except in so far as may be essential to my bottom closure.

The bottom of the completed marketable bottle embodies a flanged or skirted paper material disk 3, that is stiff or rigid and permanently centrally convexed or arched inwardly (upwardly) and thus held under tension within and closing the large end of the conical body 1. This disk 3 is permanently secured to and in the body by a lock crimp formed by the body end embracing the annular skirt or flange 3^a of disk 3.

The lower end of the conical paper body 1, is radially expanded outwardly to form downwardly facing more or less, abrupt annular seat or shoulder 1^b, and depending approximately cylindrical portion 1^c, of enlarged diameter.

The disk 3 is tightly seated and wedged against said annular shoulder 1^b and the disk flange 3^a tightly fits within the enlarged cylindrical portion 1^c of the body. The annular angular edge portion of the disk 3, at the junction between the disk body and its flange, is held compressed against the annular shoulder 1^b by the crimp that locks the disk to the body.

The disk 3 and its depending flange, enter a substantial distance into the lower end of the body, and the disk is locked in and to the body to form a permanent liquid tight joint by any suitable means, preferably by any suitable cooperating formation of the body end and

disk flange rendered stiff and permanent by paraffin or other suitable stiffening and preferably waterproofing substance or material. For instance, in the particular example illustrated, the surplus or extra end length of the body is spun, rolled or crimped inwardly and upwardly to cover the annular lower edge and inner side or surface of disk flange 3^a and to tightly abut against the bottom surface 10 of disk 3 to form a crimp 1^d, preferably with the end extremity 1^e of the body wall turned outwardly and forming an elbow pressed against the disk and constituting a lock against loosening of the crimp. 15 The disk flange 3^a and the body wall end forming the crimp are swaged and compressed together longitudinally of the bottle and toward the annular shoulder 1^b of the body so that the flange 3^a may be swaged 20 longitudinally into the crimp, to hold the disk rigidly and permanently to and against the shoulder 1^b and against loosening.

The flanged disk 3 is of enlarged overall diameter or is oversize with respect to the internal diameter of the bottle body at or below shoulder 1^b, to form and maintain the enlarged cylindrical portion 1^c and the shoulder 1^b of the bottle body and the upwardly or inwardly convexed form of the disk, all with 25 the end in view of producing and maintaining a liquid tight joint between disk and body and maintaining the disk in permanent relative position in the body to avoid variation of the internal capacity of the bottle, after the completion of the bottle.

After these paper bottles have been otherwise completed, they are usually treated externally and internally with liquid paraffin or other suitable waterproofing and stiffening 40 material, which on hardening may coat the paper walls, as indicated in a decidedly exaggerated manner by Fig. 3, and one object of the arched or upwardly convexed bottom 3 is to cause the liquid waterproofing material 45 within the bottle to drain to the annular joint 3^b and there harden to stiffen and aid in rendering said joint thoroughly liquid proof.

The main object of employing the bottom disk of oversize or enlarged diameter is to 50 produce and maintain a tight permanent seal between the disk and body and cause the disk to assume and maintain the arch or convexity toward the bottle mouth and a consequent radially outward tension against the surrounding end portion of the body. These 55 paper bottles are of necessity constructed of certain rated capacity, which capacity must be usually indicated on the exterior of the bottle. The bottle must be so made as to reduce to the minimum possibility of the bottle being increased or decreased in capacity by 60 deformation due to handling, shipment, the weight of the contents or from other causes. Heretofore, one cause for the change in capacity 65 of paper bottles, has been due to the bulging

of the bottom disks before or after the bottles have been filled, and another cause has been the failure to absolutely fix the relative longitudinal position of the disk within the bottle.

In my bottle, the enlargement of the bottle body by the disk 3 and the formation of the shoulder 1^b, permanently fixes the relative position of the disk and prevents possibility of upward movement thereof while the tight fit and oversize and tension of the disk and the crimp hold the disk permanently against downward movement. The permanent upward convexity of the disk is produced during the method of applying and fixing the disk in the bottle and the natural tendency of the disk to resume its natural flat form, particularly under the weight of the bottle contents, aids in maintaining the liquid tight joint between the disk and the bottle body and the permanently fixed position of the disk in the body.

In the method of bottoming conical paper bottles, according to my invention, the extra length open end conical paper body 1, is placed in a tapered hollow mandrel 4, with the large open end of the conical paper body projecting upwardly through and a distance above, a ring die 5 forming the upper end of the mandrel. The upper end of this ring die 5 forms an enlargement 5^a, providing a shoulder forming step surrounding the upper end of the bore of the die and this enlargement 5^a is surrounded by a vertical cylindrical wall formed by the inner surface of upstanding cylindrical flange 5^b, at the top of the die. The tapered large end of the paper body projects through the die and a distance above the same, and past the enlargement 5^a and annular lip or edge 5^b.

Referring to Figs. 4, 5, 6, I show a reciprocating punch die 7 for cutting flat large diameter disks 3, from a web of paper a, fed across ring die 6, and delivering each flat disk in the die 6, onto the internal upwardly facing shoulder 6^a, within said die 6, see Fig. 5, and to thereon hold the flat disk pending a disk flanging operation. While the flat disk is thus held on the flange forming shoulder 6^a, a disk flanging plunger 8 descends through the hollow or ring punch die 7, and enters the die 6 and engages the central portion of flat disk 3 and draws or forces said disk 3 through the contracted bore of die 6 and thereby forms the disk 3 with annular flange or skirt 3^a of the dimensions required. The mandrel 4 during this operation is held longitudinally and accurately aligned with said die 6 and the plunger and spaced therefrom with the large projecting open end of the tapered barrel 1 opposite the discharge end of the ring die 6. The parts are so arranged and proportioned, that the plunger 8 will carry the flanged disk directly from die 6 into the large projecting end of the paper body, and will drive said

flanged disk into the body and utilize the same as a die in expanding, swaging, and shaping the body end into and to conform to the enlargement 5^a and the annular lip 5^b, 5 see Fig. 6. The end face 8^a, is convexed to produce the desired inward bulge of the disk 3 when within the bottle body.

The diameter of the working end of the plunger 8, is less than the contracted bore of 10 flanging die 6 and the internal diameter of the cylindrical end 1^c of the bottle body, and hence the flanged disk fits on the working end of said plunger with its flange exteriorly surrounding said end and is thus forced into 15 the enlarged end of the paper barrel until the shoulder formed by enlargement 5^a and the paper shoulder 1^b thereon, arrests further inward movement of the flanged disk and plunger within the barrel end. The oversize 20 flanged disk thus swages the paper body into the enlargement 5^a and against the annular lip 5^b and the disk is thereby rigidly compressed against the shoulder 1^b and the wall 1^c and the meeting paper surfaces are approximately amalgamated together by the 25 high pressure.

During the process of drawing the flat disk 3, Fig. 5, into annularly skirted or flanged form by the drawing action of the dies 8 and 30 6, the drag of the flange or skirt forming action, will stretch the body of the disk 3 across and to the bottom face of the die or plunger 8 and cause said body of the disk to assume under tension, the convexed form of the bottom face of the plunger 8, and the disk is held to this convexed form as it enters the upper end of the paper body 1 in the hollow mandrel. However, the disk 3 is not molded or swaged to a permanent non-resilient 35 convexed form by being jammed and crushed between opposing dies. The disk is drawn under tension to this convex form but constantly tends to flatten out to its normal or original flat condition. Under this constant tendency to return to its normal flat condition, this disk in the completed bottle, is held under tension in its convexed form and hence 40 constantly exerts radial pressure against the inner surface of the annular radial enlarged portion 1^c of the paper body wall, as herein set forth.

When this step of inserting the disk and conforming the bottle body thereto, is completed, the plunger 8, is withdrawn, and the 45 mandrel and its bottle body containing the disk are brought into position for crimping. Any suitable means, such as a rotary crimping head, then acts on the projecting cylindrical end of the paper body to lock the 50 flanged disk in the body, as by the formation of the crimp hereinbefore described. During this crimping operation pressure is applied to the crimp longitudinally of the paper body and toward the small end thereof, and this 55 pressure is sustained by the shoulder formed

by enlargement 5^a, and hence the position of the flanged disk within the body is not changed. It is hence possible to apply the desired heavy pressure during the crimping operation without forcing the flanged disk into the paper body beyond the position predetermined and necessary in a bottle of the desired rated capacity. 70

No claims are herein made to the method of and the apparatus for bottoming paper 75 containers, disclosed hereby, as such method and apparatus are claimed in my divisional application Serial No. 283,399, filed June 6, 1928.

It is evident that various changes, modifications and variations might be resorted to without departing from the spirit and scope of my invention and hence I do not wish to limit myself to the exact disclosures hereof. 80

What I claim is:

1. A bottle embodying a paper material body longitudinally tapering from a large bottom rim to a small top mouth, said body having a permanent relatively-fixed bottom closure embodying a flanged paper material 90 disk of oversize spanning the interior of the large end portion of said body and permanently secured therein by crimping, said disk being centrally convexed inwardly and thus permanently held under tension exerting outward radial pressure against said body, said body having a radially enlarged portion and annular shoulder receiving and against which said disk is permanently held, said disk maintaining the formation of the body providing said enlargement and shoulder. 95

2. A bottle embodying a paper material body longitudinally tapering from a large bottom rim to a small top mouth, said body having a permanent relatively-fixed bottom closure embodying a flanged paper material disk of oversize spanning the interior of the large end portion of said body and permanently secured therein by crimping, said large end of the body being maintained by 105 said disk radially enlarged with the formation of an annular shoulder against which said disk is tightly held inwardly, said disk being held under tension convexed inwardly and being fixed against longitudinal movement in said body. 110

3. A bottle embodying a longitudinally tapered body of paper material and the like at its large end portion radially enlarged in diameter and having a downwardly facing 120 annular shoulder, and a flanged paper material disk permanently fixed in said enlarged portion of the body by crimping and held upwardly in tight engagement with said shoulder, said disk being centrally convexed 125 upwardly and thus held under tension with a constant tendency to return to flat form whereby the circumference of the disk is held under constant expanding tendency against the inner surface of the body. 130

4. A bottle of fixed rated capacity embodying a longitudinal body of paper material and the like having a permanent liquid tight bottom closure embodying an oversize disk 5 fixed in said body against relative longitudinal movement, the lower end of the body forming a tight disk holding crimp providing the bottle with a depending annular bottom rim, said disk forming and maintaining 10 the end of the body receiving the same with an annular shoulder seating against and stopping inward movement of the disk and an annular radial enlargement, said disk being swaged into and inset in the body while con- 15 vexed inwardly to reduce its circumferential diameter and thus held under constant tendency to return to flat form, whereby the circumference of the disk is driven radially outwardly under constant expanding ten- 20 sion against the inner surface of the surrounding annular portion of the body.
5. A bottle of fixed rated capacity embodying a longitudinally tapered paper barrel composed of a folded paper sheet having its 25 ends overlapping and secured together to form the liquid tight seam throughout the length of the barrel, said barrel provided with a permanent tight bottom closure comprising an inset resilient upwardly convexed paper 30 disk fixed within the barrel against relative longitudinal movement and a disk holding crimp of the barrel end forming the bottle with an annularly depending rim below the

disk, said disk being of over-size and shaping the barrel to form a shoulder fitting the top 35 face of the disk and an annularly radial enlargement surrounding and fitting the circumference of the disk and holding the disk under tension in its convexed form.

6. A tapered paper container including a 40 longitudinally tapered liquid tight sheet paper barrel, the lower end portion of which is enlarged in diameter thereby forming said barrel with an intermediate downwardly facing shoulder joining said enlarged end 45 and the adjacent tapered portion; and a transverse permanent inset bottom closure driven within said barrel end and against said shoulder, said bottom closure including a transverse upwardly convexed resilient 50 paper disk having an annular depending flange, said disk being held in its convexed form within said enlarged barrel end by a depending annular stiff rim of enlarged external diameter with respect to the adjoining 55 tapered portion of the barrel, said radially enlarged rim formed by crimping together the disk flange and the barrel end, whereby the load of the bottle contents on the convexed disk tends to maintain the liquid tight 60 joint between the disk and bottle body.

In testimony whereof I have hereunto set my hand at Fulton, N. Y., this 13th day of Mar., 1924.

WILLIAM H. BREMMERMAN.
